Patented January 17, 1905.

UNITED STATES PATENT OFFICE.

ARTHUR QUINTON WALSH, OF NEW YORK, N. Y.

DESIGN FOR A RECEPTACLE FOR TOBACCO, CIGARS, AND CIGARETTES.

SPECIFICATION forming part of Design No. 37,295, dated January 17, 1905.

Application filed December 14, 1904. Serial No. 236,880. Term of patent 7 years.

To all whom it may concern:

Be it known that I, ARTHUR QUINTON WALSH, a subject of the King of Great Britain, residing at the city of New York, borough of 5 Manhattan, in the county and State of New York, have invented a new, original, and ornamental Design for a Receptacle for Tobacco, Cigars, and Cigarettes, reference being had to the accompanying drawing.

10 The figure is a perspective view of a receptacle, showing my new design.

What I claim as new, and desire to secure by Letters Patent, is—

The ornamental design for a receptacle for tobacco, cigars and cigarettes as shown.

ARTHUR QUINTON WALSH.
